(57) **CLAIM**

The ornamental design for a shoe sole, substantially as shown and described.

DESCRIPTION

FIG. 1 is a perspective view of the shoe sole according to the present invention.

FIG. 2 is a side view of the shoe sole according to the present invention.

FIG. 3 is an opposite side view of the shoe sole according to the present invention.

FIG. 4 is a front view of the shoe sole according to the present invention.

FIG. 5 is a rear view of the shoe sole according to the present invention; and,

FIG. 6 is a bottom view of the shoe sole according to the present invention.

The broken lines shown in the drawings are directed to environmental structure that forms no part of the design to be patented.
